(57) **CLAIM**

The ornamental design for a cycling computer, as shown and described.

DESCRIPTION

FIG. 1 is a topside perspective view of a cycling computer showing our new design.

FIG. 2 is a topside perspective view of the cycling computer showing the cycling computer mounted to the front of a bicycle.

FIG. 3 is a top plan view thereof.

FIG. 4 is a bottom plan view thereof.

FIG. 5 is a left side view thereof.

FIG. 6 is a right side view thereof.

FIG. 7 is a front elevation view thereof; and,

FIG. 8 is a back elevation view thereof.

The broken lines shown in the drawings represent visible environmental structure or unclaimed portions of the structure of the cycling computer, and form no part of the claimed design. The broken lines showing portions of a bicycle in FIG. 2 illustrated visible environmental structure; all other broken lines in the drawings show unclaimed portions of a cycling computer. The shade lines in the drawings show contour and not surface ornamentation.

1 Claim, 6 Drawing Sheets
